ADJUSTABLE HEAD FOR LAMP SOCKETS

Filed April 26, 1935

UNITED STATES PATENT OFFICE

2,048,493

ADJUSTABLE HEAD FOR LAMP SOCKETS

William Dabgin, New York, N. Y.

Application April 26, 1935, Serial No. 18,339

5 Claims. (Cl. 173—324)

This invention relates to new and useful improvements in adjustable heads for lamp sockets.

The invention has for an object the construction of adjustable heads which are each characterized by a solid cylindrical body supporting a positive and a negative pole, a hollow semi-spherical shell having a pair of parallel spaced slots and mounted on said cylindrical body, and a pair of conductor strips pivotally mounted on said positive and negative poles and extending through said slots and pivotal along the slots, and at their outer extremities supporting a lamp socket. The arrangement permits the lamp socket to be pivoted in a plane parallel with the planes of the slots in the semi-spherical shell. A feature of the construction resides in the fact that the conductor strips performs a joint function, namely, the pivotal supporting of the lamp socket and the conducting of the electric current to the lamp socket.

A further important object of the invention is the provision of novel means for insulating the conductor strips from the hollow semi-spherical shell so as to prevent short circuiting.

More particularly, the invention contemplates the provision of insulation material encasing the conductor strips, and insulation blocks mounted on the conductor strips and slidably arranged along the edges of the slots in the semi-spherical shell in a particular manner.

A further object of the invention is the provision of a means for converting a floor lamp into a table or bridge lamp or vice versa.

A further object of the invention is the construction of a device as described which is simple and durable and which can be manufactured and sold at a reasonable cost.

For further comprehension of the invention and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a lamp with an adjustable head constructed according to this invention.

Fig. 2 is an elevational view of a wall bracket with an adjustable head constructed according to the same invention.

Fig. 3 is an elevational view of a ceiling bracket with an adjustable head constructed according to this invention.

Fig. 4 is a fragmentary perspective detailed view 55 of the adjustable head embodying the invention.

Fig. 5 is a horizontal sectional view taken on the line 5—5 of Fig. 4.

Fig. 6 is a fragmentary vertical sectional view taken on the line 6—6 of Fig. 4.

Fig. 7 is a horizontal sectional view taken on the line 7—7 of Fig. 6.

Fig. 8 is a sectional view taken on the line 8—8 of Fig. 6.

Fig. 9 is a side elevational view of an adjustable socket according to this invention equipped with a shield shown in section.

Fig. 10 is a plan view of Fig. 9.

Fig. 11 is a side elevational view of a floor lamp, the parts thereof being separated from each other merely for illustrative purposes, showing several adjustable heads according to this invention.

The invention may best be understood by first examining Figs. 4—8 inclusive. The adjustable head comprises a solid cylindrical body 10 supporting a positive pole 11 and a negative pole 12. A hollow semi-spherical shell 13 having a pair of parallel spaced slots 14 is formed with a base cylindrical portion 13^a mounting upon said cylindrical body 10. A pair of conductor strips 15, 16 are pivotally mounted on said positive and negative poles, one conductor strip on each pole, and extend through the slots 14 and are pivotable along said slots. A lamp socket 17 is supported upon the conductor strips 15 and 16 and electrically connected therewith. The conductor strips 15 and 16 are insulated against being short circuited with the edges of the slots 14 as hereinafter further amplified.

The cylindrical body 10 is mounted within a casing 10^a which is provided with a nipple 10^b at its bottom extremity. This nipple is adapted to be mounted upon various electrical fixtures as shown in Figs. 1, 2, 3, and 11. In Fig. 1 the nipple 10^b is shown supporting the cylindrical body upon a lamp 20. This lamp is of conventional hollow construction so that wires, not shown, may pass therethrough and through the nipple 10^b to reach the poles 11 and 12. The details of these wires and their connection with the poles will not be given in this specification since such construction is generally known in the art. Attention is called to the strips of material 21 and 22 extending through passages in the solid cylindrical body 10. These strips connect with the wires not shown for the supply of electricity.

The base cylindrical portion 13^a of the hollow semi-spherical shell is removably supported by reason of a plurality of depressed portions 23 from the sides thereof frictionally engaging the outer surface of the casing 10^a.

The pole 11 is integral with a transverse bar 11^a attached by screws 24 upon the top surface of the body 10. The pole 12 is set into a transverse groove 10^b in the top of the body 10 merely for the purpose of holding it against lateral play, and is held fixedly in position with a screw 25. Pintle rivets 26 serve to pivotally connect the lower ends of the conductor strips 15 and 16 with the poles 11 and 12. The lamp socket 17 is of conventional construction and is adapted to hold a lamp, such as lamp 28. The details of the socket will not be given in this specification, but to facilitate the understanding of the construction it is stated that the socket is formed with a shell contact into which the lamp 28 screws, and an end contact which electrically connects with the end contact of the lamp 28. The conductor strip 15 connects with one of the contacts of the socket 17 and the conductor strip 16 with the other contact so as to form the electric circuit through the socket and thus through the lamp.

The conductor strip 15 is encased with sheet insulation material 15' and the conductor strip 16 is encased with sheet insulation material 16'. An insulation block 29 is mounted upon each of the conductor strips and upon the insulation covering material thereof and is of a width so that one side 29^a thereof is adapted to be in intimate contact with one side of the slot 14, and the diametrically opposite side 29^b of the block is formed with a groove 29^c simultaneously engaged on the diametrically opposite edge of the slot 14.

The arrangement is such that the groove 29^c restrains the insulation block from moving longitudinally in the slot 14. The groove 29^c is of arcuate shape corresponding with the curvature of the semi-spherical shell, and the pintles 26 are arranged upon the axis of the semi-spherical shell so that the block 29 may freely move during pivoting of the conductor strips.

The slots 14 are formed with cutouts 14' of a sufficient length to receive the blocks 29 so that the conductor strips 15 and 16 may be manually flexed laterally to disengage the grooves 29^b when it is desired to remove the hollow semi-spherical shell 13 from its position, which may be necessary for repairing the device. Springs 30 are mounted on the socket 17 in the vicinity of the cutouts 14' and normally engage against the sides of the insulation material 15' and 16' of the conductor strips to normally prevent the accidental engagement of the blocks 29 into the cutouts 14'.

In Fig. 1 the dot and dash lines of the lamp indicate the extremities of the adjustability of the lamp. The lamp may be moved to any intermediate position. Friction between contacting parts is depended upon to maintain the lamp as set.

In Fig. 2 a wall bracket 32 is shown secured upon a wall 33, and supports one of the adjustable heads according to this invention. The wall bracket 32 is provided with a hollow stem 33 through which the electric wires (not shown on the drawing) pass. The nipple 10^b is attached on the extremity of the stem 30. The dot and dash lines in this figure indicate the extreme positions of adjustment of the lamp 28.

In Fig. 3 a ceiling bracket 34 is shown attached to a ceiling 35. This ceiling bracket is provided with a hollow stem 36 through which the electric wires (not shown on the drawing) pass. The nipple 10^b of the adjustable head is attached on the end of the stem 36. The dot and dash lines represent the extremities of adjustment of the lamp 28. The parts may be recognized by

numerals corresponding with numerals of identical parts in the previous description.

In Figs. 9 and 10 an adjustable head is shown provided with a shell 38. This shell comprises an inverted cup extending over the semi-spherical shell and attached upon the lower end of the socket 17. The purpose of this shell is to prevent uninformed persons from inserting metallic objects through the slots 14 which may produce a short circuit.

In Fig. 11 a lamp base 20 is shown converted into the floor base of a lamp stand by an electrical connector 40. This connector is adapted to receive and electrically connect with a head piece 41 upon which two of the adjustable heads 15 are mounted. The parts of the adjustable heads may be recognized by the reference numerals which correspond with the parts previously described. The base 20, connector 40 and head piece 41 are provided with self contained electrical wiring.

The connector 40 is provided with a screw plug 40' at one end adapted to engage a corresponding female member 20' and at the other end of connector 40 a female member 40^a is provided which is adapted to receive a corresponding screw plug 41^a. This arrangement makes it possible to safely convert one type of lamp into another without changing any of the wiring.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. An adjustable head for lamp sockets, comprising a solid cylindrical body supporting a positive and a negative pole, a hollow semi-spherical shell having a pair of parallel spaced slots formed with a base cylindrical portion mounted upon said cylindrical body, a pair of conductor strips pivotally mounted on said positive and negative poles coaxial with an axis of the semi-spherical shell and extending through said slots and pivotable along the slots, a lamp socket supported on said strips, and insulation on the strips for protection against short circuiting with the edges of the slots, comprising sheet covering material upon the strips and insulation blocks on the covering material for supporting the lamp in the adjusted position.

2. An adjustable head for lamp sockets, comprising a solid cylindrical body supporting a positive and a negative pole, a hollow semi-spherical shell having a pair of parallel spaced slots and formed with a base cylindrical portion mounted upon said cylindrical body, a pair of conductor strips pivotally mounted on said positive and negative poles coaxial with an axis of the semi-spherical shell and extending through said slots and pivotable along the slots, a lamp socket supported on said strips, and insulation on the strips for protection against short circuiting with the edges of the slots, comprising sheet covering material upon the strips and insulation blocks on the covering material, said insulation blocks having one of their sides slidably engaging one of the sides of the slots and the other of their sides formed with grooves engaged with the other sides of the slots.

3. An adjustable head for lamp sockets, com-

- prising a solid cylindrical body supporting a positive and a negative pole, a hollow semi-spherical shell having a pair of parallel spaced slots and formed with a base cylindrical portion mounted upon said cylindrical body, a pair of conductor strips pivotally mounted on said positive and negative poles coaxial with an axis of the semi-spherical shell and extending through said slots and pivotable along the slots, a lamp socket supported on said strips, and insulation on the strips for protection against short circuiting with the edges of the slots, comprising sheet covering material upon the strips and insulation blocks on the covering material, said insulation blocks having one of their sides slidably engaging one of the sides of the slots and the other of their sides formed with grooves engaged with the other sides of the slots, each of the said slots being formed with a cut out area to permit the conductor strip to be flexed so that the block engages therein and the groove thereof disengages from the edge of the slot.
4. An adjustable head for lamp sockets, comprising a solid cylindrical body supporting a positive and a negative pole, a hollow semi-spherical shell having a pair of parallel spaced slots and formed with a base cylindrical portion mounted upon said cylindrical body, a pair of conductor strips pivotally mounted on said positive and negative poles coaxial with an axis of the semi-spherical shell and extending through said slots and pivotable along the slots, a lamp socket supported on said strips, and insulation on the strips for protection against short circuiting with the edges of the slots, comprising sheet covering material upon the strips and insulation blocks on the covering material, said insulation blocks having one of their sides slidably engaging one of the sides of the slots and the other of their sides formed with grooves engaged with the other sides of the slots, each of the said slots being formed with a cut out area to permit the conductor strip to be flexed so that the block engages therein and the groove thereof disengages from the edge of the slot.
5. An adjustable head for lamp sockets, comprising a solid cylindrical body supporting a positive and a negative pole, a hollow semi-spherical shell having a pair of parallel spaced slots and formed with a base cylindrical portion mounted upon said cylindrical body, a pair of conductor strips pivotally mounted on said positive and negative poles coaxial with an axis of the semi-spherical shell and extending through said slots and pivotable along the slots, a lamp socket supported on said strips, and insulation on the strips for protection against short circuiting with the edges of the slots, comprising sheet covering material upon the strips and insulation blocks on the covering material, said insulation blocks having one of their sides slidably engaging one of the sides of the slots and the other of their sides formed with grooves engaged with the other sides of the slots, each of the said slots being formed with a cut out area to permit the conductor strip to be flexed so that the block engages therein and the groove thereof disengages from the edge of the slot, and means for normally holding the strips against flexing into positions in which the blocks engage in the cutouts.
